FASTENER STRIP PRODUCING MACHINE

William J. Parsons, 1141 E. McMurray; Dewey Holloway, 1129 E. 11th St.; and James A. Redmond, 601 W. Crane St., all of Casa Grande, Ariz.

Filed May 16, 1961, Ser. No. 110,380
8 Claims. (Cl. 1—125)

This invention relates to a fastener strip producing machine and more particularly to a fastener strip producing machine which automatically manufactures short fabric strips having snap-type fastener elements secured thereto.

Manually operated machines have been used for the fixing of snap-type fastener elements on strips of fabric and such machines have required constant attention of at least one laborer or operator. Such an operator usually manually trips the machine for the securement of each snap fastener element on a strip of fabric.

In the production of fastener strips used in the production of underwear, and other similar garments, it has been found advantageous to place two or more snap fastener elements on a fabric strip, so that a complementary snap fastener element, on the garment, may be selectively snap-locked to one of the snap fastener elements on the strip, providing adjustability of the garment in accordance with the size of the wearer.

Accordingly, machines have been operated manually to secure snap fastener elements in spaced relation longitudinally of fabric strips, and operators of such machines have been employed manually to trip such machines for the securement of each snap fastener element on the fabric strip and have then been required to manually cut off the strip so that each strip may contain two or more snap fastener elements in spaced relation longitudinally of the strip.

The end product of such manual operations is used as an adjustable fastener in connection with various garments, and accordingly, many thousands of these snap fastener strips have been produced manually at a high labor cost.

Accordingly, it is an object of the present invention to provide a fastener strip producing machine which will automatically secure snap fastener elements on a fabric strip in longitudinal spaced relationship thereon, and which will also automatically cut the strip into desired lengths, whereby each section of the strip carries two or more snap fastener elements secured thereto.

Another object of the invention is to provide a fastener strip producing machine comprising basic snap fastener securing mechanism of a conventional machine, which are automatically controlled by attachments thereto; said attachments controlling said mechanism for automatically securing snap fastener elements in spaced relation longitudinally of a strip and automatically cutting the strip into short sections, each carrying a plurality of snap fastener elements.

Another object of the invention is to provide a fastener strip producing machine having a snap fastener securing head intermittently operable by means of a clutch energized intermittently by means of switch elements, operable by switch actuating portions on a wheel, the periphery of which is provided with recesses disposed to receive snap fastener elements after they are secured on a fabric strip by said head, whereby the wheel automatically times the intermittent operation of the snap fastener securing head and advances the fabric strip.

Another object of the invention is to provide a very simple means for controlling and timing the operation of a fastener strip producing machine in order, accurately, to space snap fastener elements on a fabric strip and to cut the strips between such snap fastener elements,

2

whereby the strips are cut into short lengths, each carrying a plurality of snap fastener elements.

Another object of the invention is to provide a fastener strip producing machine having a simple timing wheel 5 provided with annular rows of switch actuating portions on opposite sides thereof; the switch actuating portions on one side of said wheel being spaced twice the angular distance, in degrees, of the switch actuating portions on the other side of the wheel, whereby, the more closely spaced switch actuating portions intermittently cause energization of the snap fastener head of the machine to secure fasteners on a strip of fabric in longitudinally spaced relationship thereon, and whereby, the more widely spaced switch actuating portions energize a cut off mechanism which intermittently cuts the strip of fabric between the snap fastener elements, secured thereon, so that each cut off strip carries a plurality of longitudinally spaced snap fastener elements thereon.

A further object of the invention is to provide a fastener strip producing machine which saves a substantial amount of labor in the production of short fabric strips each having a plurality of snap fastener elements secured thereto.

An additional object of the invention is to provide a fastener strip producing machine which is very simple and economical of construction in proportion to its utility, and which is very durable and easy to maintain.

Other objects and advantages of the invention may be apparent from the following specification, appended claims, and accompanying drawings in which:

FIGURE 1 is a fragmentary side elevational view of a fastener strip producing machine, in accordance with the present invention;

FIGURE 2 is a fragmentary end view of a fastener strip producing machine, in accordance with the invention, taken from the line 2—2 of FIGURE 1;

FIGURE 3 is an enlarged fragmentary plan view taken from the line 3—3 of FIGURE 1;

FIGURE 4 is a fragmentary sectional view taken from the line 4—4 of FIGURE 3 showing the view rotated substantially 90 degrees;

FIGURE 5 is an enlarged fragmentary sectional view taken from line 5—5 of FIGURE 1;

FIGURE 6 is an enlarged fragmentary sectional view taken from the line 6—6 of FIGURE 1;

FIGURE 7 is an enlarged fragmentary side elevational view of a timing wheel of the fastener strip producing machine of the invention, showing portions thereof, broken away and in section to amplify the illustration;

FIGURE 8 is a fragmentary plan view taken from the line 8—8 of FIGURE 7 showing the structure rotated substantially 90 degrees from that as shown in FIGURE 7;

FIGURE 9 is an enlarged fragmentary view taken from the line 9—9 of FIGURE 1;

FIGURE 10 is a fragmentary end view of the fastener strip producing machine of the invention, taken from the line 10—10 of FIGURE 1; and

FIGURE 11 is a fragmentary plan view taken from the line 11—11 of FIGURE 10.

As shown in FIGURE 1 of the drawings, the invention relates to a fastener strip producing machine which comprises a snap fastening head 20, such as disclosed in Patents 1,860,148; 1,499,270; and 1,499,203 and more particularly to a machine such as Model 41B produced by the Scovill Manufacturing Company, of Waterbury Connecticut.

This snap fastener securing head 20 is provided with a conventional punch 22, or snap element securing member, disposed to be projected into the proximity of a table 24 on which a strip of fabric is disposed, for securing snap fastener elements to said strip of tape, as will be hereinafter described.

As shown in FIGURE 1 of the drawings, the punch 22

is operated by a conventional crank press head 26, coupled in a conventional manner to a sprague clutch 28, shown in FIGURE 2 of the drawings. This sprague clutch 28 is provided with a conventional sprague controlling ring having a projection 30, the rotation of which, is interrupted by a conventional trip arm 32.

Thus, each operating cycle of the punch 22 and its crank mechanism 26 may be controlled by a downward pivotal movement of an arm 32 about the axis of a pin 34 so that the projection 30 of the sprague controlling ring may be released and permit the sprague clutch to engage, thereby causing the crank mechanism 26 to actuate the punch 22 for one cycle.

It will be understood that the arm 32 may intermittently stop the projection 30 of the sprague controlling ring during each revolution thereof. This controls each respective revolution of the crank mechanism 26 and the cycle operation of the punch 22. All of this mechanism is conventional to the machine hereinbefore referred to and generally disclosed in the aforementioned patents.

A bracket 36 supports reels 38 and 40 of fabric tape by means of projecting trunnions 42 and 44, respectively. These reels of tape may be composed of various fabric or other material as desired and are dispensed over rollers 46 and 48 in directions as indicated by arrows A and B in FIGURE 1 of the drawings. The strips of tape 50 and 52 passing from the reels 38 and 40 over the respective guide rollers 46 and 48, pass through respective wire loops 54 and 56, coupled to pivoted mercury switches 58 and 60.

These switches 58 and 60 are in circuit with electric motors of the machine, as will be hereinafter described, automatically to stop the machine when the supply of tapes 50 and 52 are exhausted from the reels 38 and 40. It will be understood that when either tape 50 or 52 is exhausted and passes the respective loop 54 or 56, that the respective switch 58 or 60 will shut off operation of the machine.

After passing through the loops 54 and 56, the tapes 50 and 52 pass over additional respective guide rollers 62 and 64. The tape strips 50 and 52 then pass into a flat guide tube 65, wherein these strips of tape are directed in flat contiguous relationship to each other and move through a guide 66 to a position on the table 24, directly below the punch 22, or snap element securing member. The tape is also extended beyond the location of the punch 22 and is driven by a timing roller 68, as will be hereinafter described.

The punch 22 of the machine head 20 is adapted to secure snap fastener elements 69 to the fabric strip, composed of the sections 50 and 52, these tape sections being superimposed so that the tape strip 50 is uppermost, as shown in FIGURE 3 of the drawings.

Positioned on the table 24 are tape guides 70 and 72. These guides 70 and 72 are disclosed in detail in FIGURES 3 and 4 of the drawings.

As shown in FIGURE 4 of the drawings, the guide 70 is an angle-shaped in cross-section guide, adjacent to which an edge 73 of the fabric tape moves. It will be seen from FIGURE 1 of the drawings that the tape is moved generally in the direction of the arrow c, on the upper surface of the table 24, in the direction toward the timing wheel 68.

The tape guide 72, as shown in FIGURES 3 and 4 of the drawings, is secured to the table 24, by a screw 74, and this guide 72 is provided with a clip section 76, which overlies the upper surface of the tape strip 50, tending to hold it down on the table 24 and to prevent lateral displacement thereof, as will be hereinafter described.

Adjacent, the guide 70, is a microswitch 78 having a pivoted arm 80, which overlies the guide 70, and is provided with a section 82, located in close proximity to the upper surface of the tape strip 50. This arm portion 82 is disposed to be engaged, by upwardly extending nib portions 84 of the snap fastener elements secured, to the

5 fabric tape 50 by the punch 22, hereinbefore described. The spring loading of the microswitch 78 is very slight and tends, resiliently to move the arm 80 to a broken line of position D, shown in FIGURE 3 of the drawings, whenever the snap fastener elements 69 are not secured to and carried by the tape 50. This may occur when the supply of snap fastener elements becomes exhausted from the hopper 84 of the head 20. Thus, the microswitch 78, with its arm portion 82, is a normally open switch and is maintained in closed condition, when the nibs 84 of the snap fastener elements hold the arm portion 82 in the solid line position, as shown in FIGURE 3 of the drawings.

Referring now to FIGURES 1 and 7 of the drawings, it will be seen that the timing wheel 68 is provided with spaced recesses 86, located in the periphery thereof. The structure of the wheel surrounding these recesses 86 may constitute means for engaging the snap fasteners or any other suitable spaced means may be utilized to perform an equivalent function of engaging such fasteners. These recesses 86 are disposed to receive the nib portions 84, of the snap fastener elements 69, secured to the composite tape comprising the strips 50 and 52, hereinbefore described. The timing wheel 68 is rotatably driven in a direction of an arrow E, in FIGURE 7 of the drawings, by a low speed motor 88, shown in FIGURE 10 of the drawings.

The motor 88 shown in FIGURE 10 of the drawings is preferably a low speed reduction gear type motor having an output shaft 90 journaled in bearings 92 and 94, supported on an auxiliary frame section 96, which is disposed on substantially a common level with the frame table portion 24 of the conventional machine head 20.

The timing wheel 68 is provided with a hub 93, which is fixed on the shaft 90, whereby the timing wheel 68 is driven at a constant rate compatible with an efficient cycle rate of the punch 22 of the machine head 20. The fabric tape strips 50 and 52 are driven along the upper surface of the table 24 by engagement of the nibs 84 in the recesses 86 in the timing wheel 68. These snap elements 69 are secured to the tape strips 50 and 52 precisely in spaced relationship to each other to match the spacing of the recesses 86 in the periphery of the timing wheel 68 as will be hereinafter described in detail.

The nibs 84 of the snap elements are maintained intimately disposed in the recesses 86 of the timing wheel 68 as it rotates in the direction of arrow E by a slide plate 98 disposed directly below the periphery 100 of the timing wheel 68.

This slide plate 98 as shown in FIGURE 8 of the drawings, is made of spring steel and is supported by a block 102, engaging the lower surface of the slide plate 98. This block 102 is made of resilient material such as rubber or its equivalent, so that it provides a resilient bearing tending intimately to force the slide plate 98 upwardly against the lower surface of the fabric tape strip 52, in order to maintain the nibs 84 of the snap elements 69 intimately engaged in the recesses 86 in the periphery of the timing wheel 68.

The block 102 is provided with trunnions 104 extending from opposite sides thereof and these trunnions 104 are mounted in plates 106 disposed adjacent side plates 108 stationarily connected to a pivoted table section 110 secured by a hinge 112 to the auxiliary frame 96.

Bolts 114 and 116 extend through the plates 106 and 108 as shown best in FIGURE 7 of the drawings, and springs 118 and 120, respectively, surround the bolts 116 and 118 and bear resiliently on the plate 106 tending to force it toward the plate 108 and also tending to force the resilient block 102 against the lower surface of the slide plate 98.

The springs 118 and 120 are retained on the bolts 114 and 116 by means of screw-threaded nuts 122 and 124, respectively.

The spring 118 and 120 permit yielding action of the

block 102 away from the wheel 68 to accommodate fastener elements which may be misplaced relative to the recesses 86.

Intermittent operation of the punch 22, hereinbefore referred to, is controlled by pins 126, or equivalent switch actuating portions, arranged in an annular row at one side of the control wheel 68 and projecting axially parallel to the shaft 90 about which the control wheel 68 is rotatably mounted. The pins 126 are disposed successively to engage a roller 128 of a microswitch 130, which is electrically coupled to a solenoid 132, shown in FIGURE 2 of the drawings.

As the control wheel 68 rotates in the direction of arrow E, each pin 126 successively engages the roller 128 and energizes the solenoid 132, whereby its armature 134 is retracted and a resilient connector 136 pivots a latch bar 138 about the axis of a fulcrum pin 140.

This fulcrum pin 140 is stationarily mounted on the frame of the machine head 20, all as shown best in FIGURE 2 of the drawings. The latch bar 138 is provided with a projecting portion 142 which engages the lever member 32 hereinbefore described. A spring 144 tends to support the latch bar 138 and hold it upwardly in order to permit the bar 32 intermittently to stop the sprague retainer at its projecting portion 30 once during each revolution of the sprague clutch mechanism and a respective cycle operation of the punch 22 as hereinbefore described.

It will therefore be appreciated that each time the microswitch 130 is actuated by one of the pins 126, engaging the roller 128 that the armature 134 is retracted into the winding of the solenoid 132. The latch bar 138 is thus forced downwardly at its projecting portion 142 causing pivotal movement of the bar 32 about the axis of the pin 34, thereby releasing the projecting portion 30 of the sprague retainer of the sprague clutch 28. This action permits the clutch to engage and to operate the crank mechanism 26 and force the punch 22 to secure a snap element 69 on the fabric strips 50 and 52 as hereinbefore described.

The microswitch 130 is vertically adjustably mounted on a bracket 146 so that the position of the roller 128 in respect to the pins 126 will cause the punch 22 to locate a snap fastener element on the tape in a position to eventually coincide with one of the recesses 86 in the periphery of the timing wheel 68. In operation the microswitch is adjusted vertically until the disposition of the snap fastener element 69 on the tape strips 50 and 52 coincide with the recesses 86 in the periphery of the timing wheel 68.

Projecting from the opposite side of the timing wheel 68 from the pins 126 are similar pins 148, as shown best in FIGURES 9 and 10 of the drawings. These pins 148 are spaced a distance equal to twice the spacing of the pins 126 and also disposed in an annular row at substantially the same radius as the pins 126.

These pins 148, as shown in FIGURE 9 of the drawings, are disposed to contact a plunger roller 150 of a microswitch 152, which is vertically adjustably mounted on a bracket 154, adjacent to the bracket 146, on which the microswitch 130 is mounted.

The microswitch 152 is electrically coupled to a second solenoid 156 having a retractable plunger 158, coupled by means of a spring 160 to a lever 162, which is pivotally mounted on a fulcrum pin 164, stationarily supported on the auxiliary frame 96. The lever 162 at a short distance from the fulcrum pin 164, is provided with an actuating end portion 166, which engages an end 168 of a shear lever 170, which is mounted on a fulcrum pin 172, stationarily carried on the auxiliary frame 96.

Secured to the lever 170 is a shear blade 172 which cooperates with another shear blade 174, mounted on the auxiliary frame 96. These blades 172 and 174 are in the path of fabric strips 50 and 52 on which the snap fastener elements 69 have been secured by the punch 22.

It will be appreciated that the microswitch 130 is operated twice as many times during each revolution of the timing wheel 68, as is the microswitch 152, due to the fact that the pins 148 are spaced apart twice the distance of the spacing of the pins 126.

Accordingly, as the microswitch 152 energizes the solenoid 156, it retracts its plunger 158 and pivots the arm 162 about the fulcrum pin 164. The end 166 of the lever 162 bears against the end 168 of the shear lever 170 and pivots it about the axis of the pin 172. The shear blade 172 carried by the lever 170 moves downwardly adjacent to the blade 174 and shears off the strips of tape 50 and 52. Since this shearing action occurs only once, while the microswitch 130 is operated twice, each section of tape cut off by the shearing blades 172 and 174, will carry two of the snap fastener elements 69, thus, the machine automatically produces short fabric strips, each of which is provided with a plurality of snap fastener elements secured thereto. By varying the spacing of the switch actuating portions on the control wheel, two or more snap fastener elements 69 may be carried by each section of tape cut off by the shearing blades 172 and 174.

These flexible fabric strips, having two or more snap fastener elements 69, may be secured to a garment and utilized to provide for two or more adjustment positions for the securing of a cooperating snap fastener element. As for example, the strips 50 and 52 may be secured to one flap of a garment shirt while a female snap fastener may be secured to the other flap of the garment shirt and the female fastener may be engaged and snapped on to a nib 84 of either of the male snap fastener elements 69 carried by the strip sections 50 and 52 secured to the garment.

It will be obvious to those skilled in the art that, while the separate fabric strips 50 and 52 are disclosed, it may be desirable to place the snap fastener elements 69 on a single layer strip of material. Accordingly, the machine of the invention will operate in a similar manner to that herein described and will shear off the fabric strips precisely to include a section of flexible strip material carrying a plurality of snap fastener elements.

It will be seen that the lever 170 carrying the blade 172 is retracted upwardly by a spring 176 following each downwardly shearing action of the blade 172. Thus, the fabric strip carrying the snap fastener elements 69 secured thereto, may pass over the shearing edge 174 for successive shearing actions by the blade 172.

As shown in FIGURE 1 of the drawings, a chute 178 is provided to receive the fastener strips as they are sheared by the shearing blades 172 and 174.

As shown in FIGURES 5 and 6 of the drawings, the pivoted table portion 110 is connected to the auxiliary frame 96 by a hinge pin 112, and the table section may be pivoted downwardly into a position as indicated by broken lines F in FIGURE 5 of the drawings to permit the flexible fabric tape to be initially inserted between the periphery of the timing wheel 68 and the slide plate 98 hereinbefore described.

A bracket 180 is secured to the pivoted table section 110 and this bracket 180 is held upwardly toward the periphery of the timing wheel 68 by means of a toggle mechanism 182. This toggle mechanism 182 is provided with a bar 184 which engages a pin 186 of the bracket 180 and tends to apply upward force to hold the table 110 in the solid line of position shown in FIGURE 5, thereby to retain the fabric tape strips 50 and 52 in close proximity to the periphery 100 of the timing wheel 68.

The toggle mechanism 182 is provided with a handle portion 188 which when moved downwardly in a direction of an arrow G in FIGURE 5 of the drawings, unlocks the toggle and permits downward movement of the arm 184 thereby permitting table 110 to pivot downwardly to the broken line position F and allow clear-

ance to thread the fabric tape between the periphery of the timing wheel 68 and the slide plate 98, as hereinbefore described.

Carried on the pivoted table section 110 between the timing wheel 68 and the blades 172 and 174 is a channel guide section 190 having a pair of upstanding channel leg portions 192 and 194 between which opposite edges of the tape sections 50 and 52 are guided.

A spring loaded clip 196 is disposed above the tape strips and in close proximity to the periphery of the timing wheel 68 in order to strip the tape therefrom in the event a fastener nib 84 becomes stuck in a recess 86 in the periphery of the timing wheel 68. As shown in FIGURE 6 of the drawings, the clip member 196 is spring loaded by a spring 198 which tends to exert force downwardly on the clip 196. The spring 198 is retained by a bolt 200 which is secured by a nut 202 at the lower portion of the table 110 as shown best in FIGURE 6 of the drawings.

Another guide 204 is disposed adjacent to the timing wheel 68 as shown in FIGURE 7 of the drawings, and this guide 204 is also adapted to maintain alignment of the tape and the nibs 84 of the snap fastener elements 69 with the periphery of the timing wheel 68 and the recesses 86 therein. This lateral alignment of the tape strips 50 and 52 with the timing wheel 68 is important so that the nibs 84 of the snap fastener elements 69 will precisely nest in the recesses 86 as the wheel rotates and draws the tape along the upper surface of the table 24 as will be hereinafter described.

In operation, the reduction gear motor 88 rotates the shaft 90 at a low speed so that the timing wheel 68 is rotated at a speed to control operation of the machine head 20. The punch 22 applies the snap fastener elements 69 to the strips of tape 50 and 52 hereinbefore described. The cycle rate of the head 20 and its punch 22 is controlled by the frequency at which the pins 126 contact the roller 128 and close the microswitch 130 which conducts electrical energy to the solenoid 132.

Thus, each time a pin 126 actuates the microswitch 130, the solenoid 132, as hereinbefore described, operates the sprague clutch 28 and causes the crank mechanism 26 to cycle the punch 22 and secure one snap fastener element to these strips of fabric 50 and 52.

As hereinbefore described, the disposition of the microswitch 130 is arranged to trigger operation of the punch 22 so that the respective snap fastener elements 69 will be located longitudinally of the tape strips 50 and 52 to coincide with recesses 86 in the periphery of the timing wheel 68 as the tape is pulled thereunder by engagement of the recesses 86 with the nibs 84 of the snap fastener elements 69. Thus, the timing wheel 68 drives the strips 50 and 52 by tension and feeds them under the punch 22 to receive the snap fastener element 69. Concurrently, the pins 148, on the opposite side of the wheel from the pins 122, intermittently actuate the microswitch 152 which energizes the solenoid 156 and intermittently actuates the blade 172, relative to the blade 174, to cut strips of the fabric tape 50 and 52 each carrying two of the snap fastener elements 69, as shown best in FIGURE 10 of the drawings.

In the event the rolls of fabric tape 38 and 40 become exhausted, and the tape strips 50 and 52 being drawn therefrom, pass beyond the rollers 62 and 64, respectively, the loops 54 and 56 connected to the mercury switches 58 and 60 become released from the strips of tape 50 or 52 and are permitted to pivot downwardly about the axis of the rollers 62 and 64. These switches are coupled to the electrical circuit controlling the entire machine and stop it whenever the supply of tape strips 50 or 52 or either of them becomes exhausted from the rolls 38 and 40.

Additionally, in the event the snap fastener elements 69 are exhausted from the hopper 84 as hereinbefore described, the arm 80 of the microswitch 78, as shown

in FIGURE 3, may pivot over to a broken line of position D and this switch 78 is also coupled to main electrical circuit of the entire machine to stop operation thereof, when the snap fastener elements are not secured to the tape strips 50 and 52. It will be appreciated that as long as the nibs 84 of the snap fastener elements 69 project upwardly, they hold the arm 80 in the solid line of position shown in FIGURE 3 of the drawings and thus hold the switch 78 closed and the machine remains in operation.

It will be obvious to those skilled in the art that various modifications of the present invention may be resorted to in a manner limited only by a just interpretation of the following claims.

We claim:

1. In a fastener strip producing machine, the combination of: a machine head; a first means in said machine head disposed to secure snap fastener elements on a flexible strip of material; a timing wheel having a means engageable with snap fastener elements fixed to said flexible strip by said first means; clutch means disposed to intermittently operate said machine head; a solenoid for actuating said clutch means; switch means operable by said timing wheel for energizing said solenoid; second switch means intermittently operable by said timing wheel, a second solenoid coupled thereto for energization thereby; and shear means operable by said second solenoid for shearing sections of said flexible strip intermediate said snap fastener elements.
2. In a fastener strip producing machine, the combination of: a machine head; a punch in said machine head disposed to secure snap fastener elements on a flexible strip of material; a timing wheel having a means engageable with snap fastener elements fixed to said flexible strip by said punch; clutch means disposed to intermittently operate said machine head; a solenoid for actuating said clutch means; switch means operable by said timing wheel for energizing said solenoid; second switch means intermittently operable by said timing wheel, a second solenoid coupled thereto for energization thereby; and shear means operable by said second solenoid for shearing sections of said flexible strip intermediate said snap fastener elements, first and second annular rows of switch actuating portions carried by said timing wheel and operably engageable with said first and second switch means for intermittently operating the same, said second mentioned switch actuating portions being spaced apart a distance equal to the spacing of a plurality of said first switch actuating portions on said wheel, whereby, said punch is operated a plurality of times for securing a plurality of snap fastener elements on said flexible strip while said shearing blades are actuated only once in order to shear off sections of said flexible strip bearing a plurality of said snap fastener elements.
3. In a fastener strip producing machine, the combination of: a machine head; a punch in said machine head disposed to secure snap fastener elements on a flexible strip of material; a timing wheel having a means thereon engageable with snap fastener elements fixed to said flexible strip by said punch; clutch means disposed to intermittently operate said machine head; a solenoid for actuating said clutch means; switch means intermittently operable by said timing wheel for energizing said solenoid; second switch means intermittently operable by said timing wheel, a second solenoid coupled thereto for energization thereby; and shear means operable by said second solenoid for shearing sections of said flexible strip intermediate said snap fastener elements, first and second annular rows of switch actuating portions carried by said timing wheel and operably engageable with said first and second switch means for intermittently operating the same, said second mentioned switch actuating portions being spaced apart a distance equal to the spacing of a plurality of said first switch actuating portions on said wheel, whereby, said punch is operated a plurality of times for securing a plurality of snap fastener elements on said flexible strip while said shearing blades are actuated only once in order to shear off sections of said flexible strip bearing a plurality of said snap fastener elements.

of times for securing a plurality of snap fastener elements on said flexible strip while said shearing blades are actuated only once in order to shear off sections of said flexible strip bearing a plurality of said snap fastener elements, a slide plate adjacent said timing wheel and disposed to hold said flexible strip in continuous relation with said wheel whereby, said snap fastener elements are firmly engaged herewith; and resilient means engaging said slide plate and tending to force it toward said wheel for intimately retaining said flexible strip in contiguous relationship with said timing wheel.

4. In a fastener strip producing machine, the combination of: a machine head, first means therein for securing snap fastener elements to a strip of flexible material; second means disposed intermittently to drive said head and intermittently to actuate said first means; a driven timing wheel having spaced recessed portions in its periphery disposed to receive snap fastener elements secured on said flexible strip by said first means; third means disposed resiliently to maintain said flexible strip and snap fastener elements in contiguous relation with the periphery of said timing wheel; a first annular row of switch actuating portions on said timing wheel; a first switch intermittently operable thereby; means coupling said switch with said second means for intermittently energizing the same and intermittently operating said first means of said machine head whereby snap fastener elements are secured to said flexible strip by said first means to coincide with the snap fastener element receiving recess portions in the periphery of said timing wheel; a second annular row of spaced switch actuating portions carried by said timing wheel; a second switch intermittently operable by said second switch actuating portions; shearing means disposed to cut off sections of said flexible strip bearing snap fastener elements; and fourth means coupled to said second switch for actuating said shearing means to cut off said flexible strip in short sections.

5. In a fastener strip producing machine, the combination of: a machine head; first means therein for securing snap fastener elements to a strip of flexible material; second means disposed intermittently to drive said head and intermittently to actuate said first means; a driven timing wheel having spaced recessed portions in its periphery disposed to receive snap fastener elements secured on said flexible strip by said first means; third means disposed resiliently to maintain said flexible strip and snap fastener elements in contiguous relation with the periphery of said timing wheel; a first annular row of switch actuating portions on said timing wheel; a first switch intermittently operable thereby; means coupling said switch with said second means for intermittently energizing the same and intermittently operating said first means of said machine head whereby snap fastener elements are secured to said flexible strip by said first means to coincide with the snap fastener elements receiving recess portions in the periphery of said timing wheel; a second annular row of spaced switch actuating portions carried by said timing wheel; a second switch intermittently operable by said second switch actuating portions; shearing means disposed to cut off sections of said flexible strip bearing snap fastener elements and fourth means coupled to said second switch for actuating said shearing means to cut off said flexible strip in short sections, said second switch actuating portions carried by said timing wheel spaced apart a greater number of de-

grees than the spacing of said first mentioned switch actuating portions whereby, a plurality of snap fastener elements may be secured to said strip during each time said shearing means is cycled.

5 6. In a fastener strip producing machine, the combination of: a machine head; first means in said machine head disposed to secure snap fastener elements on a flexible strip of material; a timing wheel having a means engageable with snap fastener elements fixed to said flexible strip by said first means; third means for intermittently operating said machine head; a fourth means for actuating said third means; switch means intermittently operable by said timing wheel for energizing said fourth means; second switch means intermittently operable by said timing wheel; fifth means coupled to said second switch means; and shear means operable by said fifth means for shearing off sections of said flexible strip intermediate said snap fastener elements.

7. In a fastener strip producing machine, the combination of: a machine head; first means therein for securing snap fastener elements to a strip of flexible material; second means disposed intermittently to drive said head and intermittently actuate said first means; a driven timing wheel having means disposed to engage snap fastener elements secured on said flexible strip by said first means; third means disposed resiliently to maintain said flexible strip and snap fastener elements in contiguous relation with the periphery of said timing wheel; a first annular row of switch actuating portions on said timing wheel; a switch intermittently operable thereby; means coupling said switch with said second means for intermittently energizing the same and intermittently operating said first means of said machine head whereby snap fastener elements are secured to said flexible strip by said first means to coincide with said snap fastener element engaging means of said timing wheel; a second annular row of spaced switch actuating portions carried by said timing wheel; a second switch intermittently operable by said second switch actuating portions; shearing means disposed to cut off sections of said flexible strip bearing snap fastener elements; and fourth means coupled to said second switch for actuating said shearing means to cut off said flexible strip in short sections.

8. In a fastener strip producing machine, the combination of: a first means therein, for securing snap fastener elements to a strip of flexible material; second means disposed intermittently to actuate said first means; a driven timing wheel having spaced recessed portions in its periphery disposed to receive snap fastener elements secured on said flexible strip by said first means; third means disposed resiliently to maintain said flexible strip and snap fastener elements in contiguous relation with the periphery of said timing wheel; a first annular row of switch actuating portions on said timing wheel; a switch intermittently operable thereby; means coupling said switch with said second means for intermittently energizing the same and intermittently operating said first means of said machine head whereby snap fastener elements are secured to said flexible strip by said first means to coincide with the snap fastener element receiving recess portions in the periphery of said timing wheel; and fourth means adjacent said timing wheel for stripping said strip away from the periphery of said timing wheel when a snap fastener element becomes stuck in one of said recess portions.
